UNITED STATES PATENT OFFICE.

JOHN NEIL, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 18,565, dated January 30, 1883.

Application filed November 28, 1882. Term of patent 3½ years.

To all whom it may concern:

Be it known that I, JOHN NEIL, of New York, in the county and State of New York, have invented a new and original Design for a Carpet, 5 of which the following is a specification.

The accompanying photograph illustrates a face view of my new design for carpet.

This invention relates to a new design for carpet and analogous fabrics; and it consists of 10 the new configuration of groups and figures that make up the ground-work of the carpet.

The carpet is subdivided into four principal stripes, (marked B, C, E, and D.) The stripe B has an outer border, b, containing a zigzag ornamentation, and an inner border, e, containing a row of figures, each of which is composed of three circles placed in line. The stripe C contains inner leaf-like ornaments, f, and rosettes d, as shown. The stripe E is composed of diagonally-placed bars, which are ornamented with rows of dots, substantially as shown. The stripe D is composed of a border-band, e, and an outer narrower band, a, the one, e, containing diamond-shaped figures, as 15 shown.

I claim—

1. The design for carpet, consisting of the stripe B, having the border b c, substantially as shown.
2. The design for carpet, consisting of the 30 stripe C, having ornamental figures f d, substantially as shown.
3. The design for carpet, consisting of the stripe E, substantially as shown.
4. The design for carpet, consisting of the 35 stripe D, having bands e a, substantially as shown.
5. The design for carpet, consisting of the figures B and C, borders b c, and figures f d, substantially as shown. 40
6. The design for carpet, consisting of the stripe B, having borders b c, stripe C, having figures f d, and stripe E, substantially as shown.
7. The design for carpet, consisting of the 45 stripe B, having borders b c, stripe C, having figures d f, stripe E, and stripe D, having bands e a, substantially as shown.

JOHN NEIL.
